UNITED STATES PATENT OFFICE.

DANIEL E. SPEICHER AND ELROY CHAS. FAUST, OF URBANA, INDIANA, ASSIGNEES TO
THE CYCLONE MANUFACTURING COMPANY, OF URBANA, INDIANA.

FEED TROUGH.

Application filed July 8, 1925. Serial No. 42,240.

This invention relates to a feed trough, designed primarily for use in the feeding of fowls, but it is to be understood that a trough, in accordance with this invention, can be employed for any purposes wherein it is found applicable, and the invention has for its object to provide, in a manner as hereinafter set forth, a feed trough comprising a container or body portion and a removable apertured cover or lid therefor and with the container and cover having coacting means for detachably securing the cover in closure position with respect to the container and in a manner to prevent the cover from being accidentally shifted from off the container.

A further object of the invention is to provide, in a manner as hereinafter set forth, a feed trough for the purpose referred to, including a cover and a container and with the cover provided with means for hooking on either side edge of the container and on the application of pressure to the cover the said means provides, in connection with the container, a fastener to prevent the removal of the cover other than by shifting the same longitudinally with respect to the container.

A further object of the invention is to provide, in a manner as hereinafter set forth, a feed trough for the purpose referred to, including a container and a cover or lid therefor, and with the latter provided with longitudinally extending means capable of engaging over the side walls of the container for connecting the cover therewith, and with said means so constructed whereby when desired, the cover can be removed from the container by shifting the cover from off one end of the container.

Further objects of the invention are to provide, in a manner as hereinafter set forth, a feed trough, which is simple in its construction and arrangement, strong, durable, compact, thoroughly efficient in its use, readily assembled, and inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications

can be resorted to which come within the scope of the claims hereunto appended.

In the drawings wherein like reference characters denote corresponding parts throughout the several views:

Figure 1 is a top plan view of a feed trough, in accordance with this invention.

Figure 2 is a side elevation thereof.

Figure 3 is a section on line 3—3, Figure 1.

A feed trough, in accordance with this invention, is constructed from sheet metal of suitable gage, and comprises a trough-like container for the feed and a cover or lid for the container and with the cover and container having coacting means for detachably securing the lid in position. The container, as well as the lid, is preferably stamped from sheet metal to the shape as illustrated.

The trough-like container or body portion is substantially rectangular in plan and consists of a bottom 1, a pair of oppositely inclined side walls 2, 3 and a pair of end walls 4, 5, which are oppositely inclined with respect to each other. The bottom 1 is formed centrally thereof with a lengthwise extending up-set portion 6, forming a reinforcing rib, and each corner of the bottom 1 is formed with a hollow depending semi-spherical portion 7, and the said depending portion 7 constitutes supports to maintain the bottom 1 above the surface of the ground. Each corner of the container or body portion is corrugated, as at 8, for reinforcing the same. Each end wall increases in height towards the center thereof from each of the side walls. The setting up of the container or body portion in the manner as stated, provides the same of flaring contour, not only at its sides but at its ends.

The cover or lid is referred to generally by the reference character 9 and inclines downwardly in opposite directions from its longitudinal center, as indicated at 10, 11. The cover 9 is of a width to project beyond the top edges 12 of the side walls 2, 3 of the container or body portion.

The portion 10, as well as the portion 11 is provided with a set of spaced transversely extending oval-shaped openings 13 and with the sets disposed longitudinally of the cover and said openings are provided to enable the fowls to have access to the feed within the

container or body portion. The material which surrounds each opening 13 is up-set to provide a reinforcing rib 14 of oval contour. The material of the cover, between the 5 openings of each set, is up-set, as at 15, to form reinforcing ribs which terminate in the ribs 14. The cover 9 is furthermore provided with up-set portions 16 extending from each outer rib 14 of a set, and said up-set portions 10 16 form reinforcing ribs.

The cover or lid 9 is of a length to project from the end of each of the side walls of the container, and each side of the cover or lid 9 is formed with a lengthwise extending angle-shaped depending resilient fastener member, referred to generally by the reference character 17. Each fastener member consists of a depending latching arm 18 of a length greater than a side wall of the 15 container. The latching arm 18 inclines inwardly throughout towards a side wall of the container. The arm 18 extends in the same inclined plane throughout. The arm 18 at its lower end merges into an outwardly extending downwardly inclined arm 19 of the same length as the length of a side wall of the container and of less length than the length of the arm 18. The arm 19 extends in the same inclined plane throughout. The arm 18 20 has each end edge thereof inwardly curved as at 20, thereby providing for the said arm 18 to be of greater length than the arm 19. The arm 19 has each end terminal thereof reduced in width, as indicated at 21. The 25 arms 19 form supports for the cover prior to the latching of the latter to the side walls of the body portion or container by the arms 18.

The side walls 2, 3 of the container or body portion coact with the arms 18 of the fastener member 17 for detachably securing the cover or lid 9 to the container or body portion, see 30 Figure 3, and to remove the cover or lid 9 after it is connected with the container or body portion, it is shifted lengthwise from off one end of the container or body portion. To secure the cover or lid 9 in position, it is 35 positioned on the top of the container or body portion and then pressure is applied to the cover or lid and it is forced into connecting position with respect to the container or body portion. When the cover is positioned on the top of the container or body portion, prior to the securing of the cover in position, it is 40 hooked over one side wall, after which pressure is applied and the cover is then connected in position to the body portion. The fastener members are of like construction but 45 oppositely disposed with respect to each other and either one of which can be hooked to a side wall prior to the application of pressure to the cover to cause the engagement of both 50 of the fastener members with both side walls of the container to detachably secure the 55 cover in position.

The cover has both sides thereof constructed alike, and in view of which the arms 19 can be seated on the upper edges of the side walls of the container, so that on the application of pressure the arms 18 can be automatically sprung to latching position with respect to the sides of the trough, that is to say the cover can be mounted on the top of the trough and when pressure is applied thereto it will be snapped to engaged or 70 latching position. Furthermore, in lieu of removing the top lengthwise of the trough, it can be pulled off vertically in lieu of longitudinally. 75

It is thought that the many advantages of 80 a feed trough, in accordance with this invention, can be readily understood, and although the preferred embodiment of the invention is as illustrated and described, yet it is to be understood that changes in the details of 85 construction can be had which will fall within the scope of the invention as claimed.

What we claim is:

1. In a latchable closure for a feed trough of that type having oppositely disposed, outwardly extending inclined side walls, the combination of a cover member of greater length than the length of said side walls, a depending inwardly inclined latching arm integral with each side of said member and of greater length than the length of a side wall, and an outwardly extending and downwardly inclined lower arm integral with each bottom of the latching arm and of a length substantially the same as a side wall 100 of the trough and providing means for supporting the cover member on the top edge of a side wall whereby on the application of down pressure to the cover member the latching arms will be swung to frictional latching 105 engagement with respect to the outer faces of said side walls.

2. In a latchable closure for a feed trough of that type having oppositely extending, outwardly disposed inclined side walls, the combination of a cover member of inverted V-shape in cross section, a depending inwardly extending inclined latching arm integral and coextensive with each side of said member, and an outwardly extending and downwardly inclined lower arm integral with the bottom of each latching arm and providing means for supporting the cover member on the top edges of said side walls whereby on the application of pressure to the cover member the latching arms will be swung to latching engagement with respect to the outer faces of said side walls. 110 115

3. In a latchable closure for a feed trough of that type having oppositely extending, outwardly disposed inclined side walls, the combination of a cover member of inverted V-shape in cross section, a depending inwardly extending inclined latching arm integral and coextensive with each side of said mem- 120 125 130

ber, and an outwardly extending and downwardly inclined lower arm integral with the bottom of each latching arm and providing means for supporting the cover member on the top edges of said side walls whereby on the application of pressure to the cover member the latching arms will be swung to latching engagement with respect to the outer faces of said side walls, said latching arms

of greater length than the length of said side walls and said lower arms of less length than said latching arms, each of said latching arms having the end edges thereof curved.

In testimony whereof, we affix our signatures hereto.

DANIEL E. SPEICHER.
ELROY CHAS. FAUST.
